UNITED STATES PATENT OFFICE

EDWIN S. PEARCE, OF INDIANAPOLIS, INDIANA, ASSIGNOR TO THE RAILWAY SERVICE & SUPPLY CORPORATION, OF INDIANAPOLIS, INDIANA, A CORPORATION OF INDIANA

AGITATOR AND CONVEYER

Application filed June 7, 1930. Serial No. 459,771.

My invention relates to conveying apparatus and, particularly, to a combined agitator and conveyer adapted for use in a number of different steps in journal box packing reclamation processes, for instance, in the steps of initial soaking of used packing, in the drying step, cleaning step, and in the final washing step, whereby such process is rendered continuous in operation and more effective as a used journal box packing renovating means.

The process above referred to relates to reclamation of used journal box packing that is made up of a plurality of fibers and is used principally as a means for maintaining lubricant adjacent a bearing and from which the lubricant seeps by capillary attraction onto or into the bearing. The reclamation process particularly referred to embodies a number of separate and distinct steps, namely, the step of initially soaking the used packing with the dirty oil which is at a temperature of substantially 200° C, then subjecting the dirty oil soaked and heated packing to an extracting operation wherein substantially all of the dirty oil is removed therefrom uniformly leaving such packing in a stage of fiber saturation only with all of the oil removed from the interstices among the fibers, then subjecting the packing to a cleaning and drying operation wherein it is conveyed through a heated current of air; then subjecting it to a washing operation wherein the packing is conveyed through and subjected to a bath of clean oil in a heated condition whereby any dirty oil lint, or loose ends remaining therein are removed; then subjecting it to another extracting action; and then impregnating the renovated packing with clean, renovated oil to the desired degree by a suitable apparatus whereby it is again ready for use in its desired capacity.

Throughout these various steps there are a number of instances wherein simultaneous conveying and agitation of the packing is desirable and it is the object of my invention to provide a conveying and agitating apparatus of such nature that the packing will be agitated, while being conveyed, to such an extent that the fibers will be shredded,

picked, pulled, loosened, and fluffed, whereby the specific reclamation operation taking place at that time, as well as subsequent operations, may be more readily and thoroughly accomplished; and to provide an apparatus of the above type wherein the packing while being conveyed through a bath of oil or other liquid will be simultaneously subjected to agitation and to a bath of the oil or other liquid imposed thereon with considerable force.

Various other objects and advantageous features of my invention may be seen in the following description and one embodiment thereof may be seen in the accompanying drawings wherein similar characters of reference designate corresponding parts, and wherein:

Fig. 1 is a sectional view showing one embodiment of my invention in combination with a tank or receptacle of the type adapted for use in a waste reclamation process;

Fig. 2 is an end view, partly in section, of the device shown in Fig. 1;

Fig. 3 is a top plan view of the device with part of the supporting elements that make up the conveyer removed;

Fig. 4 is a sectional view of a connecting rod constructed in accordance with my invention and as used in this apparatus.

Fig. 5 is a side view showing the structural relationship between the connecting rods and the supporting elements.

Referring to Fig. 1 of the drawings, I have shown a combined agitator and conveyer constructed in accordance with my invention in combination with and disposed within a tank 1 which, in a journal box packing reclamation process, is termed a soaking tank and through which the packing is conveyed and at the same time subjected to a bath of dirty oil at a temperature of about 200°, this temperature being attained and maintained by heating means 4 in the bottom of the tank. As shown, the greater portion 2 of the bottom of the tank 1 slopes toward the receiving end of the tank and a shorter portion 3 slopes toward the delivery end of the tank and intermediate the ends of these sloped bottom portions

85

90

95

100

a drain 4' is provided for the tank. It is preferable that other sloping bottom portions extend laterally downwardly from the side walls of the tank 1 to the low point in 5 the bottom wherein the drain 4' is disposed.

To have the bottom of the tank 1 sloping in the manner just described provides a tank wherein the dirt or heavy foreign material washed out of the packing being subjected to the dirty oil will tend to flow 10 down these inclined surfaces and into a relatively small area from which it may be more easily removed than if it were spread over the entire bottom of the tank. Such 15 inclined bottoms also serve to decrease the volume of oil required to maintain the oil to the proper level in the tank which is conducive to a greater circulation of the oil, easier heating and easier maintenance of the 20 temperature of the oil, and acceleration of the removal of dirt and other matter from the waste being treated.

The conveying and agitating mechanism is suspended so as to be inclined within the 25 tank 1 by means of suitable straps 5 at one end thereof and straps 6 extending downwardly along the interior side surfaces of the tank and connected to a rod 7 that extends through ears 8 on one end of the conveying and agitating frame. At the receiving 30 end of the tank, no straps such as 5 are provided but the conveying and agitating device is supported in the tank by means of straps 9, a rod or bolt 10, and ears 11, as 35 shown.

Such combined agitator and conveyer comprises suitable side rails 12 and 13 and cross members 14 and 15 to which such side rails are connected and which form bearing 40 supports for crank shafts 16 and 17 rotatably disposed at each end of the frame consisting of the side rails 12 and 13 and the cross members 14 and 15. Each crank shaft 16 and 17 embodies a plurality of crank 45 arms 38 that are preferably set on quarters opposite the crank shaft throw but each crank arm is set on the same quarter as the coinciding crank arm on the other crank shaft. These two crank shafts are operatively 50 interconnected by means of cranks 18 and 19 disposed on the ends of the respective crank shafts 16 and 17, the cranks on each side of the frame being connected together by connecting rods 20.

55 As shown in Figs. 2 and 3, the crank shaft 16 is driven by any suitable means through the medium of the shaft 21 and gear 22 disposed on the end of such shaft and meshing with a gear 23 rigidly mounted on the end 60 of the crank shaft 16. Thus, since the crank shaft 16 is operatively connected with the crank shaft 17 in the manner just described, rotation of the crank shaft 16 will cause simultaneous rotation of the crank shaft 17 65 at the same rate of speed. Both of the

shafts 16 and 17 have the same number of cranks and all cranks are, preferably, indexed in the same relative position and have the same throw. The crank shafts 16 and 17 are journaled in bearings 24 and 25 in 70 the members 14 and 15 of the frame.

A connecting rod as shown in Fig. 4 is mounted on each of the crank shafts 16 and 17 and consists of a body portion 26, a crank bearing 27 and a crank bearing cap 75 28. Side plates or sheets 29 are secured to the uppermost ends of the connecting rods and on opposing sides thereof by means of screws 30 and a cover plate 31 is secured at each end thereof on the uppermost ends 80 of the connecting rods mounted on the cranks of the crank shafts 16 and 17, respectively, the side plates and cover plates forming rails that act as connecting rods between the crank shafts. As shown in the 85 drawings, each cover plate 31 is provided with a series of louvers 32, each of which has an opening 32a and the purpose of said louvers will be hereinafter described.

In order to reduce the friction between 90 the assemblies of side plates and connecting rods on each crank of the crank shafts 16 and 17 each connecting rod is provided with annular wear plates 33 that are rigidly mounted on a threaded spindle 34 and locked 95 in position by means of jam nuts 35. Such spindle is adapted to rotate freely in either direction by being mounted in a ball bearing structure 36 on the connecting rod and the wear plates are disposed in annular openings in the side sheets 29 whereby they may abut against each other when a plurality of assemblies are mounted on the plurality of cranks which make up the crank shafts 16 and 17. 100

With this construction I have provided a combined agitator and conveyer embodying a plurality of elements so constructed and operated that the elements will have an out-of-step and oscillatory movement when 110 the device is operated and such movement will cause the material disposed on the device to be simultaneously conveyed from one end thereof to the other and agitated during such conveyance. 115

In the operation of this apparatus, the tank 1 is filled with the oil through which the used packing is to be conveyed and such oil is heated by means of the heating 120 element 4 to the desired temperature. Then, the device is operated whereupon the used waste disposed thereon will be both agitated and conveyed by the out-of-step oscillatory movement of the elements just described 125 which are inclined from their receiving to their delivery end. At the same time, each downward movement of each element will cause fluid such as air or oil to be projected upwardly through the openings 32a of 130

louvers 32 to subject the packing to a forceful oil bath.

Likewise, the device is equally applicable to use where the packing being conveyed and 5 agitated is not to be subjected to a bath of liquid. For instance, where it is desired to remove solid matter from the packing, such waste is placed upon the device whereupon the out-of-step oscillatory movement 10 of the elements will convey the packing from one end thereof to the other and simultaneously agitate the packing to cause the solid matter to be shaken therefrom. It will be 15 apparent that the device is also applicable to use in drying.

What I claim is:

1. In journal box packing reclamation apparatus of the character described, an oil-containing receptacle; a plurality of louvered, packing-supporting elements arranged within said receptacle, each of said elements having at least a portion thereof lying within said oil; and means for causing an out of step vertical oscillatory movement of said elements in said receptacle, whereby the packing on said elements is subjected to a cleaning effect by said oil.

2. In journal box packing reclamation apparatus of the character described, an oil-containing receptacle; a plurality of packing-supporting elements arranged within said receptacle, each of said elements having at least a portion thereof lying within said oil; and means for causing an out of step vertical oscillatory movement of said elements in said receptacle, said elements being provided with vertically disposed openings therethrough to enable the oil in said receptacle to flow, during oscillatory movement of said elements, through the openings in said elements onto the packing carried thereby, whereby the packing on said elements is subjected to a cleaning effect by said oil.

3. In journal box packing reclamation apparatus of the character described, an oil-containing receptacle; spaced crank shafts arranged within said receptacle and each carrying a plurality of cranks indexed in different directions; means for operating said cranks in unison; and a plurality of packing-supporting elements mounted on said cranks and vertically oscillatable by rotation thereof, said elements being provided 55 with vertically disposed openings therethrough to enable the oil in said receptacle to flow, during vertical oscillation of said elements, through said openings in said elements onto the packing carried thereby, 60 whereby said packing is subjected to a cleaning effect by said oil.

4. In journal box packing reclamation apparatus of the character described, an oil-containing receptacle; a plurality of packing-supporting elements mounted within

said receptacle, each of said elements having at least a portion thereof lying within said oil; and means for causing an out of step vertical oscillatory movement of said elements in said receptacle, said elements being provided with vertically disposed openings therethrough to enable the oil in said receptacle to be forced, during vertical oscillatory movement of said elements, through the openings therein onto the packing carried thereby, whereby said packing is subjected to a cleaning effect by said oil.

5. In journal box packing reclamation apparatus of the character described, an oil-containing receptacle; spaced parallel crank shafts in said receptacle, the adjacent cranks of each of said shafts being indexed in different directions and the coinciding cranks of said shafts being indexed in the same direction; means for operating said crank shafts in unison; and a plurality of louvered, packing-supporting elements mounted on said cranks and vertically oscillatable by rotation thereof, each of said elements having at least a portion thereof lying within the oil in said receptacle, whereby said packing is subjected to a cleaning effect by said oil.

In testimony whereof I hereby affix my signature.

EDWIN S. PEARCE.
